WIRE BASKET

Karol Kubinec, 2704 Petit St., Port Huron, Mich.

Filed Nov. 8, 1961, Ser. No. 67,417

Term of patent 14 years

(Cl. D58—4)

The figure on the drawing is a perspective view of a wire basket showing my new design. The parts of the design shown in solid lines on the handle and outer perimeter of the basket continue around as indicated by the broken lines.

I claim:

The ornamental design for a wire basket, as shown and described.
